DESIGN FOR A HANDLE FOR AN IRON

Charles S. Jackson, Elmhurst, Ill., assignor to
Merrill M. Kistner, Chicago, Ill.

Application August 12, 1940, Serial No. 94,380

Term of patent 14 years

To all whom it may concern:

Be it known that I, Charles S. Jackson, a citizen of the United States, residing at Elmhurst, in the county of Du Page and State of Illinois, have invented a new, original, and ornamental Design for a Handle for an Iron, of which the following is a specification, reference being had to the accompanying drawing, forming a part thereof.

Figure 1 is a side elevational view of a handle for an iron embodying my new design.

Fig. 2 is a rear elevational view thereof.

Fig. 3 is a top plan view thereof on a slightly enlarged scale.

I claim:

The ornamental design for a handle for an iron, substantially as shown.

CHARLES S. JACKSON.
